MEDICINAL MONOAZO COMPOUNDS

Raemer R. Renshaw, New York, and Edmond T. Tisza and Bernard F. Duesel, Yonkers, N. Y., assignors to The Pyridium Corporation, Nepera Park, N. Y., a corporation of New York

No Drawing. Application October 19, 1933,
Serial No. 694,340

6 Claims. (Cl. 260—96)

This invention relates to medicinal preparations, including ortho- and/or meta-halogen and/or alkyl substituted azo compounds for use as antiseptics and germicides, and also relates to processes for making the same.

Although many amino aromatic compounds and their derivatives are known to have physiological action, they are generally not used for medicinal or therapeutic purposes, because of their toxicity, and also because they are oxidizable in the human body to para-hydroxyl derivatives. These para-hydroxyl derivatives, even though of decreased toxicity, and even though they retain in large part the physiological action of the compounds from which they were derived, do not function satisfactorily because of the toxicity of the para-hydroxyl grouping. These phenolic hydroxyl groups readily enter into combinations including sulfonic or glucuronic acid groupings, which are inert and ineffective from a physiological viewpoint.

For example, it was early found that compounds such as aniline and acetanilide (Schmiedeberg, Archiv für experimentelle Pathologie und Pharmakologie, vol. 8, page 1, 1878) are oxidized to para-amino phenols in the human system, which last-mentioned compounds are eliminated from the system in the form of inert and ineffective combinations.

It has long been thought necessary, in order to decrease the toxicity and also to prevent the formation of such para-hydroxylated compounds, to insert a substituent group in the para-position in such amino-aromatic derivatives. According to this theory, phenacetin and a large number of other para compounds have been developed and have achieved wide spread utilization in the field of medicine.

We have now found, however, that it is possible to obtain certain ortho- and/or meta-halogen and/or alkyl substituted azotized aromatic amines of markedly decreased toxicity and enhanced therapeutic value, without regard to whether or not the para-group was substituted.

These amines are preferably produced by the diazotization and coupling of a meta and/or ortho halogen and/or alkyl substituted aromatic amine with a diamino aromatic compound, such as meta-phenylenediamine. The preferred ortho- and/or meta substituents include chlorine, bromine, io-

dine, methyl, ethyl, propyl, butyl, amyl, ethylene, propylene, butylene, etc. It is desirable to exclude certain substituent groups such as the sulphonate acid group, the alkoxy group and the hydroxy group, from these compounds.

These compounds are not particularly toxic, whether or not they are substituted in the para-position; are not converted into inert compounds even though they may contain hydroxyl groups; and are particularly of value because of their enhanced bactericidal action, and because of their elimination in the urine.

The probable structural formula of the preferred type of the meta- and/or ortho-halogen and/or alkyl substituted azo compounds of the present invention is as follows:

in which either R and/or R' may represent a halogen atom as Cl, Br, F, I, or an alkyl group, as, for example, CH₃, C₂H₅, C₄H₉, C₅H₁₁, and so forth.

The preferred method of obtaining these compounds is by diazotizing the ortho- and/or meta-halogen and/or alkyl substituted anilin and coupling the corresponding diazonium salt with m-phenylene-diamine in acid solution.

The dyes obtained are of similar character, and form from yellow to dark brown crystals, slightly soluble in water, very soluble in organic solvents such as methanol, ether, acetone, carbon tetrachloride, and toluene. For purification, they may be recrystallized out of toluene.

By recrystallization out of toluene, as well as certain other organic solvents not miscible with water such as ligroin, the compound may be prepared devoid of certain particular undesirable impurities, particularly phenolic bodies arising during diazotization.

With acids, they form salts, the hydrochlorides being dark red to bluish violet colored crystals. These salts are soluble in water, from which solution the bases may be precipitated with an alkali. The hydroxide, carbonate, or acetate of an alkali metal may be used as the alkali for this purpose.

With concentrated hydrochloric acid they also form a dihydrochloride, which is usually darker than the corresponding mono-hydrochloride.

The following examples illustrate various methods of obtaining some representative medicinal preparations of the present invention. Equimolecular quantities were used of the compounds, which were coupled together to form the azo-derivatives.

Example 1

2-methylaniline (o-toluidine), when diazotized and coupled with m-phenylenediamine, forms clusters of orange-colored needles, which, when recrystallized out of toluene, have a melting point of about 98-99° C.

The probable structural formula of this compound is:

2-methyl-2',4'-diamino-azobenzene.

Example 2

4.1 g. of 2-chloraniline (o-chloraniline) were dissolved in 150 cc. of water and 10 cc. of conc. hydrochloric acid. The solution was cooled to 2° and diazotized with a 10% solution of sodium nitrite, using starch-potassium iodide paper as indicator. The resulting diazonium salt solution was added to a solution of 5.8 g. of m-phenylenediamine hydrochloride in 100 cc. of water

The acidity of the mixture was then reduced with saturated sodium acetate solution, whereupon copulation commenced. After three hours saturated sodium chloride was added, and the hydrochloride of the dye was precipitated in dark colored crystalline form. The precipitate was collected, washed, dissolved in water and the base was precipitated with sodium hydroxide. The base, when recrystallized from toluene, forms fine orange-yellow colored needles with a melting point of about 125-126° C.

The probable structural formula of this compound is:

2-chloro-2',4'-diamino-azobenzene.

Example 3

3-methylaniline (m-toluidine), when diazotized and coupled with m-phenylenediamine, forms bead-like clusters of short, orange colored needles, which when purified by recrystallization out of toluene, have a melting point of about 95-96° C.

The probable structural formula of this compound is:

3-methyl-2',4'-diamino-azobenzene.

Example 4

2 g. of 3-butyl aniline were dissolved in 100 cc. of water and 14 cc. of concentrated hydrochloric acid. The solution was cooled down to 5° C. and a solution of 1 g. of sodium nitrite in 10 cc. of water was added, drop by drop. After all the sodium nitrite solution was added, the mixture was allowed to stand for 15 minutes and then a

few grams of urea were added to combine with the excess sodium nitrite.

The resulting diazonium salt solution was filtered and a solution of 2.4 g. of metaphenylene diamine hydrochloride in 50 cc. of water was added. The solution was made almost neutral with saturated sodium acetate solution and copulation then ensued. A red precipitate, the hydrochloride of the dye, deposited. After standing for two hours, the precipitate was collected and washed with water. The hydrochloride of the dye was then dissolved in dilute (about 2%) hydrochloric acid, filtered and the base was precipitated with sodium hydroxide. It was purified by recrystallization out of toluene with the formation of an orange colored crystalline powder, having a melting point of about 71-72° C.

The probable structural formula of this compound is:

3-butyl-2',4'-diamino-azobenzene.

Example 5

3-chloraniline (m-chloraniline) when diazotized and coupled with m-phenylenediamine, forms yellow-orange colored plates, which when purified by recrystallization out of toluene, have a melting point of about 121-122° C.

The probable structural formula of this compound is:

3-chloro-2',4'-diamino-azobenzene.

The preferred methods for making compounds have been described, but it is obvious that slight changes may be made without changing the scope of these inventions. There may be also variations in the use of intermediate compounds; therefore, we do not intend to limit ourselves to the compounds specifically described herein by way of illustration.

All the compounds above described show decided bacteriostatic and bactericidal properties, when tested by the agar plate method against *Staphylococcus pyogenes aureus* and *Bacillus coli*. The bacteriostatic and bactericidal properties vary quantitatively over a considerable range. In the case of 3-butyl-2',4'-diamino-azobenzene the bacteriostatic power against *Staphylococcus pyogenes aureus* is 1:80,000 and the bactericidal action is 1:45,000.

In the case of 2-chloro-2',4'-diamino-azobenzene the bactericidal power against *Staphylococcus pyogenes aureus* is 1:24,000 and that of 3-chloro-2',4'-diamino-azobenzene is 1:25,000. The bactericidal action of these compounds against *Bacillus coli* is less pronounced.

In general, they are more active against cocci, than they are against the rod bacilli. Some of these compounds even may be called specific against cocci.

What is claimed is:

1. As a medicinal substance an azo compound of the following structural formula:

75

in which a hydrogen atom more adjacent to the azo group than the para position is replaced by R which represents a halogen atom or a lower alkyl group.

5 2. As a medicinal substance, an azo compound of the following structural formula:

in which a hydrogen atom more adjacent to the azo group than the para position is replaced by a halogen atom.

15 3. As a medicinal substance, an azo compound of the structural formula:

where the radicle R represents an alkyl group, or halogen.

4. As a medicinal substance, an azo compound of the structural formula:

5

where the R represents an alkyl group, or halogen.

5 6. As a medicinal substance, an azo compound of the structural formula:

10

6. As a medicinal substance an azo compound of the structural formula:

15
